UNITED STATES PATENT OFFICE

WILLIAM H. ECKERT, OF NEW YORK, AND WILLIAM H. GREGORY, OF BROOKLYN, NEW YORK.

CONDUCTOR FOR HOUSE-LIGHTING.

SPECIFICATION forming part of Letters Patent No. 442,575, dated December 9, 1890.

Application filed September 15, 1890. Serial No. 364,943. (No model.)

To all whom it may concern:

Be it known that we, WILLIAM H. ECKERT, of the city, county, and State of New York, and WILLIAM H. GREGORY, of Brooklyn, county of Kings, State of New York, both citizens of the United States of America, have made a new and useful Improvement in Conductors for House-Lighting, or for other purposes requiring a distribution of electric currents among the apartments of a building, of which the following is a specification.

It is the object of our invention to effectually separate the conductors of a system one from the others, and to place each of them in a position well protected from all danger of accidental contact. To this end we surround a wire with an insulating-tube, preferably of fire-proof material, whose hollow space is of much greater diameter than the conductor itself, thus insulating it not only by the walls of the pipe, but by a wide air-space as well.

In carrying our invention into practice we prefer to permanently build the conductors into the pipes, thus avoiding the difficulty of drawing wires into long tubes after they have been placed within the walls of buildings or other inaccessible positions.

Figure 1 of the drawings represents a single length of pipe with its conductor inserted. Fig. 2 represents a means of joining the sections of pipe together. Fig. 3 is a curved pipe-section. Fig. 4 represents a modified form of coupling. Fig. 5 illustrates a means of joining a conductor with the metallic heads which are placed one in each end of a pipe-section. Fig. 6 is a modification of the arrangement shown in Fig. 5. Fig. 7 shows our improved form of conductor as applied to a form of union-box which we employ in distributing a current to different parts of a house.

A conductor *b* is centrally placed in a tube or pipe *a* of fire-proof insulating material, and is there held by insulating-plugs *c*, the latter being placed within the ends of each section.

As is more fully shown in Fig. 2, each insulating-plug *c* is provided with a central core *h* or *h'*, one having a flange *d* and the other a flange *g* to prevent such cores from being

drawn inward by the longitudinal displacement of wire *b*, to which they are attached. To effect electrical contact, core *h* is provided with a female and core *h'* with a male screw, and *f* is screwed within *e* until *d* and *g* are brought into contact with each other. The flat ends of the two sections are then brought together; but to give the conductor greater strength and rigidity a collar *k* is screwed over threaded parts *i j* to form a rigid joint.

In Fig. 4 we have shown an arrangement which is well adapted to vertical piping in which we dispense with the collar *k*, employing instead a bell-shaped end *l* for one section, within which the end of the adjoining section is inserted.

Instead of joining a conductor *b* with a core *h*, as shown in Figs. 2, 3, and 4, we find it preferable to pass the wire longitudinally through plug *c*, there making it fast by means of a screw *s*, as seen in Fig. 5. A still better arrangement is shown in Fig. 6, in which a metallic core is tightly driven into plug *c*, while the latter is in turn driven into the end of pipe *a*, and in like manner *h'* is driven into *c'* and *c'* into the end of the other section of pipe. Conductor *b*, after passing through *c*, is securely clamped by nut *y*, while the conductor of the other section is attached to *h'* by *w*. In order that the pipe ends may come into close contact, *h'* must be placed within *c'* a sufficient distance to entirely inclose nut *y*. With this arrangement the male screw *g* may be turned within *w*, thus forming an inexpensive and strong joint.

In Fig. 7 we show two tubes *t' q'*—a long and a short one—for making each loop connection to and from the union-box, the conductors within tubes *z* being joined with a common conductor *s*, placed within one compartment of the box, while wires *v* within tubes *t'* extend to a second compartment, within which is a common conductor *t*. The two conductors of each loop are carried in separate pipes *a a*, and are joined, respectively, to the entering tubes *t' q'* of the box, as already described. In this case, however, we use a collar *k*, reaching around both pipes to secure the joint. To maintain the best insulation, the wire within the tube should be 100

kept as dry as possible, and to this end the plugs *c* are made practically air-tight. If an embedded conductor were used and a part of its coating were to become moist or wet, a leak would ensue and the covering would soon be destroyed. Where, however, an air-space is employed between the pipe and the conductor, no such difficulty can arise, for then no current could pass to the pipe even

- 10 if the latter were wet. It is also obvious that by thus building a conductor in sections any part may be removed and replaced upon the discovery of a defect at any point without in any manner disarranging more than a few

15 feet of its length.

What we claim, and desire to secure by Letters Patent, is—

1. A conductor for house-wiring or other similar purposes, made in sections, each section consisting of an insulating-tube having end plugs, a centrally-arranged wire whose diameter is much less than the bore of the tube arranged therein, metallic heads placed within said plugs, to which the central wire is connected, one of said heads being provided with a male and the other with a female screw, whereby parts of the conductor may be removed by unscrewing one section from another.
2. A conductor for house-wiring or other similar purposes, made in sections, each section consisting of an insulating-tube, a single interior conductor placed within said tube, and plugs and central metallic heads placed therein, to which the conductor is joined, and a male and female screw formed within and upon said metallic heads in the ends of adjoining pipe-sections.

3. A conductor for house-wiring or other similar purposes, made in sections, each section consisting of an insulating-tube, an interior conductor, and means for joining contiguous sections, consisting in end plugs having central metallic heads or cores provided with male and female screws, substantially as 45 described, said cores being rigidly connected to the electrical conductors of the tubes.

4. A conductor for house-wiring or other similar purposes, made in sections, each being formed of a centrally-arranged conductor, a pipe having end plugs and metallic contacts, said contacts consisting in centrally-arranged metallic cores with which the wire is joined, a male and female screw formed within or upon said cores at each joint, and a pipe-coupling within which the ends of adjoining tube-sections are inserted.

5. A conductor for house-wiring or other similar purposes, made in sections, a centrally-arranged conductor, and a pipe of insulating material having end plugs *c c'*, the latter being provided with centrally-arranged metallic cores *h h'*, one having a male and the other a female screw, and a conducting-wire *b*, substantially as described.

6. In a pipe-joint for electric conductors, the combination of insulating-plugs *c c'*, cores *h h'*, male screw *g*, female screw *w*, nut *y*, fastening-screw *w'*, conducting-wires *b*, and pipe-sections *a*, substantially as described.

WILLIAM H. ECKERT.
WILLIAM H. GREGORY.
